ABEL DEFRAINE AND PIERRE VERSILLÉ, OF PARIS, FRANCE

CHARGE-MIXING DEVICE

Application filed October 9, 1926, Serial No. 140,655, and in France June 16, 1926.

The invention relates to charge mixing devices for internal combustion engines adapted to consume a mixture of air and hydro-carbon fuel and more particularly heavy fuel.

5 The invention has for its object to provide a device of this character adapted to be disposed between the engine and the carburettor operating in conjunction therewith, and to finish the mixing of the combustible mixture 10 supplied by the carburettor so as to ensure perfect carburation while at the same time realizing a substantial economy in fuel.

More specifically the invention relates to 15 apparatus of the kind comprising a series of perforated plates heated in a suitable manner, and which the combustible mixture supplied by the carburettor has to traverse, the mixture during its passage thus being successively compressed and expanded whereby 20 in combination with the friction of the mixture against the walls of the perforations a perfectly homogeneous mixture is obtained.

According to the present invention the 25 plates are each provided with a comparatively large number of conical apertures for the purpose of dividing the combustible mixture traversing the device into a comparatively large number of very small jets of mixture so that all the particles of each jet of mixture 30 are thoroughly heated, the advantages of such a constructional form of device being, further, that high temperatures for heating purposes may be avoided while permitting the attainment of a sufficiently high and 35 uniform temperature throughout the mixture.

Another advantage of the invention is that, 40 by arranging a suitable number of the plates in a series with the conical apertures in each plate in line with the corresponding apertures in the other plates and with the narrow ends of the apertures turned towards the engine, the passage of burning mixture to the carburettor, upon a back-fire taking place is 45 prevented.

In addition to the regular air inlet or inlets 50 of the carburettor an additional adjustable air inlet may be provided in the induction conduit on the carburettor side of the plates.

According to a further feature of the in-

vention each aperture in the plates may be provided with a substantially ovoid element longitudinally movable within the aperture in question so that all of the apertures may be partly closed when the engine is operating 55 under light load conditions.

The invention will now be described by way of example with reference to the accompanying diagrammatic drawings in which

Figures 1 and 2 are longitudinal and transverse sectional views respectively of one embodiment of the invention, Fig. 3 being a transverse sectional view of a modified constructional form of the invention.

Referring now to Figures 1 and 3, it will 65 be observed that the conduit 1 leading from the carburettor (not shown) is provided with a throttle valve 2, the charge mixing and atomizing device, which is mounted within the induction conduit between said throttle 70 valve and the engine 3, being secured to the latter and comprising a tubular metallic element 4 adapted to be heated by direct conduction from the engine casing. A suitable arrangement may also be provided for heating 75 said element 4 from the exhaust conduit of the engine or from water supplied from the cooling radiator of the engine. Within the tubular element 4 a series of plates 5 are mounted in intimate contact with the element 4 so that heat is conducted directly from the latter to the plates 5 which in the embodiment illustrated are relatively thick 80 for this purpose.

A comparatively large number of apertures 85 6 of conical shape are provided in the plates 5, the plates being in contact with one another and the apertures 6 in communication with one another as illustrated in the drawing. The plates 5 may however be 90 spaced apart from one another if desired.

The mixture is supplied by the carburettor associated with the device in a more or less 95 homogeneous state and flows past the throttle valve 2, when it is open, and through the series of apertures 6, thereby being subjected successively to compression and expansion and also heated before being finally drawn into the engine 3.

It is to be noted that, the narrow ends of 100

the perforations 6, being turned towards the engine 3, the passage of the burning mixture to the carburettor upon a back-fire taking place is substantially prevented.

5 In addition to the usual air intake or intakes of the carburettor, we provide an adjustable additional air intake, diagrammatically shown at 7, permitting the variation at will of the quantity of air, admitted to the 10 mixture according to the temperature and the hygrometric state of the air and to the quality of the fuel employed. When the engine is hot, and the external temperature favorable, a supplementary air admission is effected 15 through intake 7, this additional air, upon its passage through the apertures in the plates, mixing intimately with the first mixture supplied by the carburettor, thus realizing an economy in fuel.

20 In the embodiment shown in Fig. 3, rods 8 carrying substantially ovoid elements 9 are provided, these rods extending along the center lines of the apertures, and one element 9 being provided in each aperture.

25 The rods 8 are solidly joined, for example by a plate 10, and connected by a linked rod 11 to any suitable controlling device. Said device may be realized, as shown in Fig. 3, by an operative connection with the 30 throttle valve 2 of the carburetor in such a manner that the elements 9 will partly obturate the apertures 6 when the engine is running under light load conditions. A safety device may be further provided for 35 locking the rods 8 in a position in which the elements 9 completely obturate the apertures 6 thereby preventing the operation of the engine and consequently the theft of the automobile, for example, of which the engine 40 forms the power unit. Said locking device may be realized as shown, Fig. 3, by a small plate 12 which slides in the body 4 and maintains the plate 10 in the position 10_a. The plate 12 is actuated by a bent lever 13 and a 45 rod 14; said latter can be locked by any suitable bolt or padlock.

Claims:—

1. A charge mixing device for internal combustion engines comprising a tubular 50 metallic housing, a succession of superposed thick plates and in contact relation, a number of uniformly shaped conical apertures provided in the thickness of each plate being arranged in line with the corresponding 55 apertures in the other plates with the narrow end of the aperture of one plate adjacent the wider end of the aperture of the adjacent plate, the narrow ends of all the apertures being turned towards the engine.

60 2. A charge mixing device for internal combustion engines comprising a tubular metallic housing, a succession of superposed thick plates of a certain thickness and in contact relation, a number of uniformly 65 shaped conical apertures provided in the

thickness of each plate being arranged in line with the corresponding apertures in the other plates, the narrow ends of the apertures being turned towards the engine, rods extending through said apertures and so positioned as to be moved longitudinally, substantially ovoid shaped elements arranged on said rods and equally spaced apart from one another, and means to move simultaneously said rods so that the narrow ends of the apertures of the plates will be closed simultaneously by said ovoid shaped elements.

70 3. A charge mixing device for internal combustion engines comprising a tubular metallic housing a plurality of thick plates arranged in contacting relation therein each plate having a plurality of conical apertures 75 therein aligned with the apertures of the other plates and providing a plurality of parallel passages of alternating reduced and enlarged cross section the narrow ends of all the apertures being turned towards the engine.
